(57) **CLAIM**

The ornamental design for a mobile phone case, as shown and described.

DESCRIPTION

A portion of the disclosure of this patent document contains material which is subject to copyright and/or trademark protection. This patent document may show and/or describe matter which is or may become trade dress of Kardia. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a perspective view of a mobile phone case, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict environment of the mobile phone case and forms no part of the claimed design.
